UNITED STATES PATENT OFFICE.

CHARLES MONTAGUE LINLEY, OF LONDON, ENGLAND.

COIN-CONTROLLED GAME APPARATUS.

SPECIFICATION forming part of Letters Patent No. 605,494, dated June 14, 1898.

Application filed March 15, 1897. Serial No. 627,685. (No model.) Patented in England January 11, 1896, No. 730.

To all whom it may concern:

Be it known that I, CHARLES MONTAGUE LINLEY, a subject of the Queen of Great Britain and Ireland, and a resident of 42 St. Luke's road, Clapham, London, S. W., England, have invented a certain new and useful Coin-Controlled Game Apparatus, (patented in Great Britain January 11, 1896, No. 730,) of which the following is a specification.

My invention consists of a table or board made of any smooth-surfaced material or substance and provided all round with an up-standing edge. The table aforesaid is provided with holes, and the game is played by slanting the table so that a ball or balls rolls or roll by its or their own weight or weights into the holes already mentioned; and in order that my invention may be fully understood and readily carried into effect I will describe it with reference to the four accompanying sheets of drawings and to the letters of reference marked thereon—that is to say:

Figure 1 is a plan of the new coin-controlled game apparatus forming the subject of my invention. Fig. 2 is an elevation, and Fig. 3 is a sectional elevation. Fig. 4 is a section of the central tube and the coin-chute, taken at right angles to Fig. 3. Fig. 5 is a section through Z Z, Fig. 4. Figs. 6, 7, 8, 9, and 10 show how the coin is thrown off its platform.

Similar letters of reference indicate like parts throughout the figures.

a is the table or board, having the raised edge a' all round.

b b are holes formed in a, and through these holes the players endeavor to roll the balls b' by tilting the table a. The holes b may be surrounded by different-colored rings, such as b'', to distinguish the opposing sides. I prefer to have two holes b near the center of the table a; but I do not bind myself to that particular arrangement of holes nor to any particular number of balls or players.

In the annexed drawings I have illustrated a convenient method of elevating or depressing the sides of the table for giving motion to the balls. In this arrangement I provide a number of racks c and pinions d, situated at intervals around and beneath the table.

As being suitable for two players I have shown four vertical racks and four pinions engag-

ing them, all arranged at equal distances around the table. To the spindle d' of each pinion d I have a lever or finger-grip e, so that each of the players may control a rack 55 with each hand. The table a rests on the tops of the racks c, (see particularly Fig. 3,) and when any of the pinions are revolved so that a rack is raised the table is made to slant and the ball or balls to roll to the lower 60 side.

To adapt a coin-freeing mechanism to this machine, I construct the apparatus preferably in the following manner, but without confining myself to the precise position of the 65 tube and accessories.

In the center of the table a I have a vertical tube f, extending above and below. The part of f which is above the table is a complete circle in cross-section, but the part below it is cut away, so as to present only a 70 semicircular cross-section, as at f', (see Figs. 4 and 5,) within f, and free to slide therein is an inner tube h. From the holes b I provide tubes g, leading to and opening into f through holes f''. Coincident holes g' are provided in h, so that the balls b' can enter that tube also 75 and fall into the hollow plunger i, which is normally free to slide in h. The plunger i is kept from falling out of h by the bent arm 80 w. The plunger also has projecting from it the lug z. Attached to the bottom of h is the coin-platform x', z and x' being so arranged as regards one another that when in their normal positions there will be a space between them equal to rather more than the thickness of the coin x used in operating the 85 apparatus.

k is a flat tube or coin-chute projecting slopingly downward from the coin-aperture k', provided in a'', the end of k not touching x', but coming fairly close to it. k is held in position by being attached at one end to the aperture k' and also by the stay k'', attached to k and to the under side of a. Assuming 90 the balls b' to have been played and fallen down the tubes g and into h and thence into the plunger i, the tube h can be freely lifted by the knob h' without also raising the plunger i, containing the balls, there being nothing to connect i with h. At the end of h is 95 a slot i', running out at the bottom of it, and 100

the platform x' has a slot x^2 in it to prevent it (x') coming in contact with z when h is raised.

To permit the balls to be raised for a new game, a coin x is inserted at k' and, passing through k , falls on the platform x' , a portion of the periphery of x coming between z and x' . As x' is attached to h and z to i , the raising of h will cause i and the balls z x' and the coin x to go up all together, and the balls in i coming above a and in line with the holes g^2 in f will roll out onto a through the holes i^2 in i and f^3 in h . The bottom of i on which the balls rest is rounded, so as to facilitate the escape of the balls through the holes onto the table a when h is raised. In order to throw the coin x off x' , I provide an arm s , pivoted or fulcrumed at s' to the bracket t , depending from the under side of a . To one end of s is attached the spring u , the upper end of which may be attached to the under side of a . The free end of s is curved, as shown, the space between the tip s^2 and the heel s^3 being somewhat more than the diameter of the coin intended to be used. When a coin is on x' and the tube h is raised, the platform x' and coin x also go up, and s^2 and s^3 being above x' the arm s turns on its pivot and the heel s^3 passes across the coin and (when the tube is at its highest pivot) falls on the opposite side of the coin x to that which is occupied when the tube h was at its lowest position. On lowering h the heel s^3 commences to return to its former place; but instead of passing across the coin it passes across the platform, and the heel s^3 , pressing against the edge of the coin, finally pushes it off the platform into the box or receptacle v . Fig. 6 in the accompanying drawings shows the relative positions of s , s^2 , and s^3 and the coin x and platform x' before h is raised. Fig. 7 shows the relative position soon after commencing to raise h . Fig. 8 shows the relative positions when h has been raised as high as possible. Fig. 9 shows the heel s^3 beginning to slide the coin across the platform soon after h begins to be pushed down after the balls have been deposited on a . Fig. 10 shows the coin as having been finally thrown off the platform when h is between its lowest and highest positions.

l is a curved or flat glass cover placed over the table a , so as to prevent the balls being improperly removed.

m is a casing attached to the stand m' of the table. Slots or apertures n are formed in the casing m at suitable intervals, in which work pins n' , connected to the table-casing a^2 . These pins and slots act as guides for the table when tilted.

o o are springs (shown spiral in Fig. 3, but which may be of any other suitable form) attached at one end to stand m' and at the other end bearing on a washer o' or other projecting part of the rack c and tending to keep the said rack in its downward position when the finger-grip e is released.

p p are brackets, (attached to the bottom of table a .) the projections p' p' of which are bifurcated or bored to permit of the racks c passing therethrough. These brackets rest (when the table is in its normal position) on the horizontal portion of the casing m and serve to hold the table steady.

q q are tubes or hollow columns connected at the ends to the stand m' and casing m , and through these tubes the racks c pass. The horizontal tubes r , in which work the pinions d , are connected to the columns q , suitable openings being formed to allow the pinions to engage with the racks.

Having now described my invention, what I claim as new, and desire to secure by Letters Patent, is—

In the coin-controlled game apparatus hereinbefore described, the table a having the holes b ; the balls b' ; the vertical racks c ; the pinions d and levers or finger-grips e ; the vertical tube f ; the tubes g leading to the vertical tubes f and h ; the central or inner raising and lowering tube h having the platform x' on which rests the coin x ; the plunger i having the projection z ; the coin-chute k attached at one end to a^2 , and extending toward but not touching the platform x' ; the glass cover l ; the casing m provided with slots or apertures n ; the stand m' ; the guide-pins n' ; the springs o ; the brackets p p' ; the tubes q and r ; the tip s^2 and heel s^3 of the pivoted arm s ; the bracket t and spring u ; the box v and the stop w .

In witness whereof I have hereunto set my hand in presence of two witnesses:

CHARLES MONTAGUE LINLEY.
